GARDEN HOSE REEL

William A. Gerson, Vineland, N. J., assignor to Elbee
Manufacturing Co., Vineland, N. J.

Application July 22, 1957, Serial No. 47,041

Term of patent 14 years

(Cl. D41—1)

Fig. 1 is a side elevational view of a garden hose reel embodying my new design. The other side is the same.

Fig. 2 is a sectional view taken along lines 2—2 of Fig. 1.

I claim:

The ornamental design for a garden hose reel, as shown and described.
